UNITED STATES PATENT OFFICE.

GEORGE A. LUTZ, OF NEW YORK, N. Y., ASSIGNOR TO AMERICAN CIRCULAR LOOM COMPANY, OF PORTLAND, MAINE, A CORPORATION OF MAINE.

ARMORED CONDUCTOR.

No. 916,741.

Specification of Letters Patent. Patented March 30, 1909.

Application filed June 17, 1907. Serial No. 379,346.

To all whom it may concern:

Be it known that I, GEORGE A. LUTZ, a citizen of the United States, and resident of New York city, borough of Brooklyn, in the county of Kings and State of New York, have invented certain new and useful Improvements in Armored Conductors, of which the following is a specification.

The object of my invention is to provide a metallic conduit or armor for electric conductors which may be capable of bending in the nature of a flexible conduit, and in carrying out my invention I provide a plurality of longitudinally disposed strips arranged parallel side by side in circular form around a central axis and adapted to receive a conductor, such as an insulated cable, in the space within said strips, and I place a binder or winding of suitable material, such as flexible metal, around said strips to hold them in tubular relation, and I also provide means to limit or prevent relative longitudinal movement of said strips, and whereby the conductor contained within said strips is protected.

My invention also comprises the further novel details of improvement that will be more fully hereinafter set forth and then pointed out in the claims.

Reference is to be had to the accompanying drawings forming part hereof, wherein—

Figure 1 is a side elevation of a portion of an armored conductor comprising my invention; parts being broken away. Fig. 2 is a cross section on the line 2, 2, in Fig. 1. Fig. 3 is an enlarged central section substantially on the line 3, 3, in Fig. 2, and Fig. 4 is a detail perspective of a portion of one of the armored strips.

Similar numerals of reference indicate corresponding parts in the several views.

In the drawings the numeral 1 indicates strips of suitable material, such as metal, arranged longitudinally and parallel edge to edge and in a circular direction in tubular form surrounding a cable or conductor 2, and said strips may be curved transversely to substantially correspond to the curvature of said cable, as shown in Fig. 2. The strips 1 are held in place in tubular form by a binder or winding 3 which may be in the form of a metal strip and which is shown wound spirally around strips 1; and covers the joints between the longitudinal edges 55 of said strips 1. To keep the binding strip

3 in place and to prevent relative longitudinal movement of strips 1 the latter are provided with external projections 4, which may be bent up from the material of strip 1, and are shown crossing the same at an oblique angle to the longitudinal axis of strips 1, as in a spiral-like direction, so that the spirally disposed binding 3 will lie in the spaces 1^a of strips 1 between their projections 4, and the ends of the projections 4 of one strip substantially aline with the ends of the projections 4 of the adjacent strips providing spirally disposed recesses on the surface of the tubular conduit formed by the adjacent longitudinally disposed strips 1. The grooved portions of strip 1 assist in permitting said strips to bend by increasing their flexibility when arranged as set forth, and as the projections 4 engage binding 3 longitudinal movement of strips 1 is limited.

To close the joints between the adjacent projections 4 I provide a strip 5 that is wound over said projections, the strip 5 being shown grooved longitudinally to fit upon and receive said projections 4, and shown resting at its ends upon the binding 3, all whereby strip 5 is kept from displacement along the cable.

The covering or conduit may be made by first producing the projections 4 in strips 1 by any suitable means, then laying said strips lengthwise and parallel side by side around the conduit or cable 2 so that the ends of the projections 4 of one strip substantially aline with the ends of projections 4 of adjacent strips, and then the binding strip 3 is wound spirally around strips 1 in the spaces 1^a and thus the protecting covering or conduit is secured upon the cable, and the strips 1 are held from undue displacement in any direction. The resulting armored cable or conductor is protected by the covering described and yet the same may bend for carrying the armored cable around corners and in different positions.

The tubular protecting covering for the cable or conductor has a substantially smooth inner wall or surface, whereby the cable or conductor may be withdrawn from or pulled into the covering without injuring the insulation of the cable or conductor.

Having now described my invention what I claim is:

1. A protecting covering for electric conductors comprising a longitudinally disposed

- protecting envelop provided with exterior integral projections extending around the same, and a cover inclosing said envelop.
2. A protecting covering for electric conductors comprising a tubular longitudinally disposed protecting envelop provided with exterior integral projections extending around the same, and a two-part cover over said envelop.
10. 3. A protecting covering for electric conductors comprising a plurality of longitudinally disposed strips located in substantially tubular form and provided with exterior projections, and a binding strip wound upon the first named strips and between said projections.
4. A protecting covering for electric conductors, comprising a plurality of longitudinally disposed strips located in substantially tubular form and provided with spirally disposed projections on the exterior thereof, and a binding strip wound spirally around said strips and between the projections thereof.
25. 5. An armored conductor comprising an insulated cable having a tubular cover comprising longitudinal strips provided with exterior projections, and a binding around said cover.
30. 6. An armored conductor comprising an insulated cable provided with strips extending longitudinally thereon and surrounding the same, said strips being provided with exterior projections, and a binding strip wound upon the first named strips in a spiral direction.
7. An armored conductor comprising an insulated cable provided with strips longitudinally disposed and surrounding the same, said strips having spirally disposed projections on their exterior, and a binding strip wound spirally around the first named strips and between the corresponding projections thereof.
45. 8. A protecting covering for electric conductors comprising a plurality of longitudinally disposed strips located in substantially tubular form and provided with exterior projections, a binding strip wound upon the first named strips and between said projections, and a strip wound upon said projections to cover the joints between adjacent projections.
9. A protecting covering for electric conductors comprising a plurality of longitudinally disposed strips located in substantially tubular form and provided with exterior projections, a binding strip wound upon the first named strips and between said projections, and a longitudinally grooved strip wound upon said projections and receiving the same to cover the joints between adjacent projections.
10. An armored conductor comprising an insulated cable provided with strips extending longitudinally thereon and surrounding the same, said strips being provided with exterior projections, and a binding strip wound upon said first named strips in a spiral direction, and a strip wound over said projections to cover the joints between adjacent projections.
11. An armored conductor comprising an insulated cable provided with strips longitudinally disposed and surrounding the same, said strips having spirally disposed projections on their exterior, a binding strip wound spirally around the first named strips and between the corresponding projections thereof, and a grooved strip wound spirally over said projections to cover the joints between adjacent projections.
12. A protecting covering for electric conductors comprising an inner tube provided with spirally disposed projections and convolutions between the same formed of material separate from the tube, the inner wall of said tube at the parts between the projections being substantially smooth, and a jacket covering said projections and convolutions.
13. A protecting covering for electric conductors comprising an inner tube provided with corrugations extending around said tube, the inner surface of said tube between the corrugations being substantially smooth, and an outer covering secured to said corrugations and holding the same in place and covering the joints thereof.

Signed at New York city in the county of New York and State of New York this 13th day of June A. D. 1907.

GEORGE A. LUTZ.
